UNITED STATES PATENT OFFICE.

JOHN S. SMITH, OF JACKSON, MICHIGAN, ASSIGNOR OF ONE-HALF TO
THEODORE G. BENNETT, OF SAME PLACE.

MACHINE FOR TREATING CLAY.

SPECIFICATION forming part of Letters Patent No. 312,666, dated February 24, 1885.

Application filed November 10, 1884. (No model.)

To all whom it may concern:

Be it known that I, JOHN S. SMITH, of the city and county of Jackson, in the State of Michigan, have invented a new and useful Improvement in Machines for Preparing Clay, of which the following is a specification.

My improvement relates to that class of machines which are used in the preparation of clay for manufacture into tiles, pipes, &c.; and it consists in the use of a rotating disk or plate in combination with rollers revolving above the same and in proximity thereto for breaking up the lumps, kneading the clay, and expelling the stones which may be mixed with the mass.

In the annexed drawings, making part of this specification, Figure 1 is a side elevation of the machine. Fig. 2 is an end elevation of the same, and Fig. 3 is a top or plan view of the same.

The same letters are employed in all the figures in the indication of identical parts.

A is the frame of the machine. B is the driving-pulley on the shaft B', which carries the spur-pinion B² and the fly-wheel B³. The pinion B² engages the spur-wheel C on a shaft which carries the beveled pinion C', engaging the matched wheel D on a vertical shaft, D', having its step on the frame A. On the upper end of shaft D' is a circular rotating plate, E, the upper face of which, instead of being flat, as in another application filed herewith, is formed with a spiral rib or recess, e, commencing at the center and running to the periphery. It may be formed by cutting a spiral channel in the face of a flat plate, or by a raised rib, the effect in either case being to form the face of the plate in different planes with a recess and intermediate surface running spirally from center to circumference. Above this plate are placed two rollers, F and G, radially disposed, which run in near proximity to the face of the plate. In the case as illustrated one of these rollers is positively actuated by a spur-wheel, F', driven from the pinion C'; but they may be both actuated positively or both free-running,

or, as shown, with one positively actuated and the other free-running. Whether one or the other of these plans shall be adopted will depend upon the nature of the clay to be treated. Outside of the plate is a fixed curb to confine the clay. This curb is not shown in the drawings in this case. A scraper, H, is placed as shown, to throw the clay off at the periphery of the rotating plate. Another scraper, H', directs the clay as it comes from the hopper toward the center of the wheel. This hopper discharges the clay onto that part of the wheel intermediate between the scrapers H H' and the roller F. Should there be stones in the clay too large to be drawn in between the roller and the rotating plate and crushed, they will stop in front of roller F, and the spiral e, acting upon them, will cause them to roll over and over, so detaching the clay in which they are embedded and working the stones toward the periphery, passing between the roller F and the end of scraper H', finally eject them through an opening left for the purpose in the curb immediately in front of the roller F. The spiral operates not only to clean and expel the stones, but also to aid in tempering the clay by breaking up lumps and disintegrating the particles, and so bringing the mass into a condition excellently suited for the further working in the tile machine.

Among the machines heretofore employed for reducing clay to proper condition is one in which the clay as it comes from the bank is first passed between rollers and the stones taken out in a manner in common practice for many years. The clay then falls upon a rotary grating, and passing under another set of rollers is forced through narrow spaces between thin bars into a pug-mill. My machine is distinguished from this in the substitution of a solid rotating plate for the grating, and dispensing with the first set of rollers, whereby the entire work of separating the stones and reducing the clay to proper condition is performed at a single operation, the clay after twice passing under a roller being

expelled at one place on the periphery, while the stones are discharged at another opening left for the purpose in the stationary curb.

What I claim as my invention, and desire 5 to secure by Letters Patent, is—

In a machine for treating clay, the combination of a solid revolving plate and a roller or rollers rotating in proximity thereto for reducing the clay to a plastic condition and at 10 the same time expelling the stones mixed with

the clay over the periphery of the plate at one point while the clay is discharged over the periphery at another, substantially as set forth.

In testimony whereof I have hereunto set my hand in the presence of two subscribing 15 witnesses.

JOHN S. SMITH.

In presence of—

JULIAN J. BENNETT,
J. B. VIETS.
